CLAIM

The ornamental design for a calculator with electronic tube display and keypad, as shown and described.

DESCRIPTION

FIG. 1 is a perspective view of a calculator with electronic tube display and keypad showing my new design;

FIG. 2 is a perspective view thereof;

FIG. 3 is a side elevation view thereof;

FIG. 4 is a side elevation view thereof;

FIG. 5 is a side elevation view thereof; and,

FIG. 6 is a top plan view thereof.

The broken lines in the drawings depict portions of the calculator with electronic tube display and keypad that form no part of the claim.
